H. Rustad
ATTYS.

UNITED STATES PATENT OFFICE.

HENRY RUSTAD, OF WINNIPEG, MANITOBA, CANADA.

MOLDING FORM.

Application filed July 20, 1922. Serial No. 576,373.

To all whom it may concern:

Be it known that I, HENRY RUSTAD, of the city of Winnipeg, in the Province of Manitoba, Canada, have invented certain new and useful Improvements in Molding Forms, of which the following is the specification.

The invention relates to improvements in molding forms and an object of the invention is to provide a withdrawable form for molding air spaces in cement or such like self setting walls, a length of wall being preferably cast as a unit and the forms inserted therein and withdrawn prior to the wall setting.

15 A further object of the invention is to provide a form which can be quickly and easily expanded or contracted and which is constructed comparatively light, although amply strong to withstand the heavy work 20 for which it is designed.

A further object is to construct the device from relatively few parts and with the various parts connected one to the other so that the form remains intact as a unit structure 25 at all times.

A further object is to construct the device so that when withdrawn it will leave a smooth faced opening in the wall.

With the above more important objects in 30 view the invention consists essentially in the arrangement and construction of parts hereinafter more particularly described and later pointed out in the appended claims, reference being had to the accompanying 35 drawing in which:

Fig. 1 is a plan view of a portion of a cast cement wall and showing a number of air spaces cast therein and my molding form as it appears in use and prior to withdrawal.

40 Fig. 2 is a side view of the molding form.

Fig. 3 is an interior view of the molding form, the movable side plate having been dismounted.

Fig. 4 is an interior view of the movable 45 side plate.

Fig. 5 is an enlarged detailed vertical sectional view at 5—5' Fig. 2, the central part of the form having been broken away.

Fig. 6 is an enlarged detailed horizontal 50 sectional view at 6—6' Fig. 3, the section passing through the side of the form.

Fig. 7 is an enlarged detailed vertical sectional view at 7—7' Fig. 3 and looking to the right.

In the drawing like characters of reference indicate corresponding parts in the several figures.

The body part of the form comprises a stationary side 1, a movable or collapsible side 2 and similar withdrawable ends 3 and 4. The sides are identically constructed, each comprising a comparatively heavy gauge substantially rectangular sheet metal body plate 5 having reinforcing bars 6 and 7, in the present instance of angle iron, permanently riveted to their upper and lower edges and suitably spaced parallel stay bars 8, 9, 10 and 11 passing from the top to the bottom thereof and riveted to the body plate and to the bars 6 and 7. The stay bars are 70 also in the present instance formed of angle iron.

The various bars are located on the inner sides of the plates and it will be observed that the edges of the plate are projected beyond the ends of the bars 6 and 7 to form angular end flanges or wings 12 and 13.

The stationary plate is provided with upper and lower horizontally disposed sets of equi-length swinging arms 14 fastened pivotally to the flanges of the stay bars by means of loose rivets or bolts 15. The free ends of the arms of each set are connected by upper and lower parallel cross rods 16 and 17.

A pair of spaced parallel vertically disposed flat adjusting bars 18 and 19 are carried by the rods 16 and 17, the bars having their upper ends turned a quarter turn and projecting beyond the upper edges of the sides of the form. A cross bar 20 forming a handle is connected to the upper ends of the adjusting bars by bolts 21.

The swinging arms 14 are stopped in a position at right angles to the body plates 95 by engagement with substantially L-shaped brackets 22 permanently riveted to the body plate adjoining the outer sides of the bars 8 and 11 of the stationary side of the form. These brackets are used for another purpose later described.

The lowermost ends of the adjusting bars

are turned a quarter turn and terminate in outwardly flanged ends 18' and 19' and the side 2 is attached to the bars at the lower end by bolts 23 passing through the end flanges 18' and 19' and through the lower bar 7 and it has the upper end thereof fastened to the adjusting bars by angle brackets 24 riveted to the upper bar 6 and fastened by bolts 25 to the bars 18 and 19.

10 By so bolting the plate 2 it is possible to remove it at any time to inspect the interior of the form.

From the arrangement hereinbefore described it will be obvious that by forcing the bars 18 and 19 inwardly and downwardly one causes the movable plate to take its outermost position, the outermost position being reached when the arms 14 have engaged the brackets 22. At this time the plate 2 is directly opposite the plate 1.

On the other hand, if one pulls the bars 18 and 19 upwardly they cause the side 2 to shift inwardly toward the side 1, this movement being stopped when the cross rods 26 strike the flanges of the stay bars.

The ends 3 and 4 of the form are identically constructed, being each formed from comparatively heavy gauge sheet metal strips, the strips being bent into the shape best shown in Fig. 6. The said ends, it will be observed, present a vertical web 26 and a curving molding face 27 and they take a position between the flanges or wings 12 12 and 13 13 when assembled.

35 The web of each wing is pivotally connected to the inner tips of the brackets 22 by pivot arms 28. The pivot arms 28 have a horizontal position when the molding faces 27 of the ends 3 and 4 of the form are contacting with the end wings.

40 Looped handles 29 and 30 are secured permanently to the upper ends of the webs so that one can manipulate the ends 3 and 4 by pulling upwardly or shoving downwardly on the handles. A handle 31 is also secured to the bar 6 of the stationary side 1 of the form.

This molding form can be used for molding air spaces 32 in a cast cement or such like 50 wall 33, the wall being moulded between suitable retaining forms 34 and 35 indicated in dotted outline in Fig. 1. A number of the molding forms are used and they are alternated in position in the wall so that the 55 air spaces will be alternated. In actual practice I find it desirable to construct the molding form so that it will be thirty inches long when the sides are fully expanded. Then by spacing the forms two inches apart 60 I provide in the cast wall equi-spaced webs 36 two inches wide and located at thirty two inch centres which is, according to practice, the usual spacing for floor joists, indicated at 37.

65 By this arrangement the joists have their

ends carried by the webs 36, which are in reality vertical columns in the wall, carrying the joists.

The molding forms are set in proper position prior to the cement being poured and 70 they are expanded fully by forcing the handles 20, 29 and 30 downwardly.

It is desirable to wrap a sheet of building paper or such like around each expanded form. When the forms have been properly 75 positioned the cement is poured and prior to the same setting one releases the forms by pulling up on the handles. As the handles 29 and 30 are pulled upwardly the ends go in. After the ends are so withdrawn the 80 handle 20 is pulled upwardly which swings in the movable plate. When this is done the form can be bodily lifted as a unit from the wall, leaving the air space therein.

When casting walls in this manner I also 85 find it convenient to insert nailing strips 38 in the face of the wall, the strips being spaced a predetermined distance apart and having tapering sides so that they become anchored in the cast wall.

90 What I claim as my invention is:

1. A molding form comprising a stationary plate having inwardly deflected end wings, a movable plate opposing and complementary to the stationary plate and having the end wings deflected toward, but spaced from, the wings of the other plate, means connecting the plates pivotally together whereby the movable plate can be swung toward or passed away from the stationary plate, and retractable end members 95 engageable with the inner sides of the wings and normally closing the opening between the wings.

2. In a molding form, a stationary plate 100 having the end thereof provided with inwardly deflected wings, a movable plate spaced from and complementary to the stationary plate, said movable plate having deflected end wings extending towards the former wings, but spaced therefrom, vertically swingable arms connecting the plates, end members normally engageable with the inner faces of the wings and closing the opening therebetween and vertically 110 swingable pivot arms supporting the end members from the stationary plate.

3. A molding form comprising a suitably 115 interiorly reinforced stationary plate having the ends thereof inwardly deflected to provide end wings, a suitably reinforced movable plate complementary to and opposing the stationary plate, said movable plate having end wings extending towards but spaced from the wings of the stationary plate, upper and lower sets of vertically 120 swingable arms pivotally connected to the inner side of the stationary plate, cross rods connecting the free ends of the arms of the sets, vertically extending spaced adjust- 125 130

- ing bars mounted on the rods, a handle connecting the upper ends of the bars, means connecting the movable plate to the adjusting bars, similar end plates normally contacting with the inner faces of the wings and closing the openings therebetween, vertically swingable pivot arms pivotally connecting the end plates to the stationary plate and handles secured to the upper ends of the 5 end plates.
4. A molding form comprising a suitably interiorly reinforced stationary plate having the ends thereof inwardly deflected to provide end wings, a suitable reinforced 10 movable plate complementary to and opposing the stationary plate, said movable plate having end wings extending towards, but spaced from the wings of the stationary plate, upper and lower sets of vertically 15 swingable arms pivotally connected to the inner side of the stationary plate, cross rods connecting the free ends of the arms of the sets, vertically extending spaced adjusting bars mounted on the rods, a handle connecting 20 the upper ends of the bars, means connecting the movable plate to the adjusting bars, similar end plates normally contacting with the inner faces of the wings and closing the openings therebetween, stop brackets 25 permanently secured to the stationary plate 30 and engageable with certain of the swinging arms and limiting the down swinging thereof, vertically swingable arms pivotally connecting the end plates to the stop brackets
- and handles permanently attached to the 35 upper ends of the end plates.
5. A molding form comprising a pair of similar opposing spaced side plates, said plates having their inner sides suitably reinforced and their ends deflected angularly 40 inwardly to provide opposing spaced end wings, horizontally disposed upper and lower sets of vertically swingable arms pivotally connected to the inner side of one of the plates, upper and lower cross rods connecting the free ends of the sets of arms, vertically extending suitably spaced adjusting bars pivotally mounted on the rods, said bars having their upper ends projected 45 beyond the plates and passing therebetween, a handle connecting the upper ends of the bars, stops permanently secured to the latter plate and engageable with certain of the arms and limiting the down swinging of the 50 sets of arms, end plates normally engaged with the inner faces of the end wings and closing the openings therebetween, vertically 55 swingable bars connecting the latter arms to the stops, lifting handles secured to the upper ends of the end plates and means attaching the other of the plates to the adjusting 60 bars.

Signed at Winnipeg, this 10th day of June, 1922.

HENRY RUSTAD.
